UNITED STATES PATENT OFFICE.

HENRY A. BRASSARD, OF CLEVELAND, OHIO, ASSIGNOR OF ONE-HALF TO THOMAS J. DUGAN, OF CLEVELAND, OHIO.

PHONOGRAPHIC NEEDLE.

Application filed March 19, 1920. Serial No. 367,062.

To all whom it may concern:

Be it known that I, HENRY A. BRASSARD, a citizen of the United States, residing at Cleveland, in the county of Cuyahoga and State of Ohio, have invented a certain new and useful Improvement in Phonographic Needles, of which the following is a full, clear, and exact description.

The present invention relates to a needle intended for use in the reproduction of sound in connection with a phonographic record.

The object of the present invention is to provide a needle which will transmit the vibrations which the needle receives from traveling over the phonographic record, to the sound reproducer in such a fashion that these vibrations are undamped and free so that the subsequent vibrations of the air produced by the sound box are clear, sharp and distinct and convey the modulations and resonance of the voice or instrument, which originally produced the record.

Reference should be had to the accompanying drawings in which Fig. 1 shows in perspective a phonographic needle embodying the present invention; Fig. 2 is a longitudinal sectional elevation of a needle and Fig. 3 is a transverse section on the line A—A of Fig. 2.

As shown in the drawing, the needle consists essentially of a body portion such as indicated at 1, the forward portion of the body being grooved as indicated at 2 to form a V-shaped portion having the side walls 3 and 4 which intersect in a lower edge 5. These walls as shown in Fig. 3 are slightly concave so as to provide a more acute edge at 5. At the end of the needle the walls are sheared in a slanting direction as indicated in Fig. 2 so that the extreme forward point at the end of the needle is formed by the intersection of slanting planes at an acute angle.

The body of the needle is preferably formed of steel and when the point becomes dulled from use the needle may be sharpened by merely rubbing a honing stone along the slanting surface at the end, this action merely removing a part of the metal and restores the point to its initial sharpness.

The walls 3 and 4 are necessarily thin and are free to vibrate as the needle is used.

Secured at one end of the needle is a tongue 6. This tongue is as before stated, secured at one end and otherwise unsecured so that it is free to vibrate. The width of the tongue 7 is slightly less than the width between the upper edge of the walls 3 and 4. The tongue is preferably made of bronze.

As the needle is used in reproducing from a phonographic record, vibration is set up in the walls 3 and 4 as well as in the tongue 6 and these vibrations are in a measure amplified by the combined interaction of the walls 3 and 4 and the tongue 6 so that the vibrations which reach the sound box of the reproducing mechanism are clear and distinct and of much greater intensity than the vibrations which are produced by a solid needle of the usual type. The foregoing action results in the production of a clearer, louder and more resonant sound from the sound box than can be reproduced by the use of the solid needle.

The scratching sound which is commonly produced by the solid type of needle and which scratching sound is transmitted to the sound box, is very largely eliminated in the present form of needle. The form of the point which engages with the record is more of a triangular point than a round point and there is not so much of a digging-in action of the point of the needle upon the body of the record in the present needle as in the usual type of steel needles.

In the present drawing the needle is shown as triangular in shape throughout its length, but where desirable the end of the needle as indicated at 1 in the drawings may be modified in form to fit any particular form of needle holder.

Having described my invention, I claim

1. A phonographic needle having side walls which converge and form an edge which extends throughout the length of said side walls, the other edges of said side walls being free to vibrate.

2. A phonographic needle, the body portion of which is provided with walls, one edge of which is free to vibrate, and a tongue extending between the said edges.

3. A phonographic needle having slanting walls which converge, the said walls having an edge which is free to vibrate and a tongue which is also free to vibrate extending between said walls.

4. A phonographic needle having a body portion which in section is a hollow V-shape

and a tongue secured at one end to the body of the needle and extending between the said side walls.

In testimony whereof, I hereunto affix my signature.

HENRY A BRASSARD.
